United States Patent Office

Des. 188,146
Patented June 7, 1960

188,146

ROTARY WING AIRCRAFT

Leon L. Douglas, Wynnewood, Pa., assignor to Vertol
Aircraft Corporation, Morton, Pa., a corporation of
Pennsylvania

Filed Jan. 25, 1960, Ser. No. 59,163

Term of patent 14 years

(Cl. D71—1)

Des. 188,146

PAGE 2

Fig. 3

Fig. 4

Figure 1 is a side elevational view of my new design for a rotary wing aircraft.

Figure 2 is a top plan view.

Figure 3 is a front elevational view.

Figure 4 is a rear elevational view.

Figure 5 is a front perspective view.

The conventional rotor blades are shown broken away at various points in their lengths in the several views for convenience of illustration only.

I claim.

The ornamental design for a rotary wing aircraft, substantially as shown and described.
